SHOE PART ORNAMENTING MACHINE

Arthur W. Altvater, University City, Mo.

Application November 29, 1932, Serial No. 644,832

12 Claims. (Cl. 164—29)

The present invention relates, but not exclusively, to ornamenting machines for perforating, or forming ornamental cut-outs, in shoe upper parts, and more particularly to that type of ornamenting machine provided with a die having up-standing cutting edges over which the shoe upper part to be ornamented is positioned and upon which the shoe upper part is empaled by a pressing member located on the side of the shoe upper part opposite the die.

Heretofore in order to position the shoe upper part to receive the ornamentations in the desired location it has been customary to provide the ornamenting machine with a mask having an internal opening surrounding that portion of the shoe upper part in which the ornamentations are to be formed, some part of the edge of the opening in the mask being shaped to act as a gage for positioning the shoe upper part beneath the mask.

Experience has demonstrated that the appearances of the edges of the perforations or cut-outs in the shoe upper part differ on the opposite faces thereof. This difference is due to the burnishing of the edges of the perforations or cut-outs on that face of the shoe upper part into which the cutting edges of the die penetrate initially and to the formation of burs on the edges of the perforations or cut-outs on that face of the shoe upper part from which the cutting edges of the die emerge.

Heretofore it has been highly desirable that the finished face of the shoe upper part be the face into which the cutting edges of the die penetrate initially in order that the edges of the cut-outs or perforations shall present to view in the finished shoe a burnished appearance.

In using a shoe part ornamenting machine of the mask type heretofore the face of the shoe part opposite the face which is gaged by the mask is the one provided with the perforations or cut-outs having the attractive burnished edges. Heretofore in using a mask it has been necessary often to register some portion of the finished face of the shoe upper part with the gaging edge on the mask with the result that the edges of the cut-outs or perforations on the finished face of the shoe upper part are burred and not burnished.

The principal object of the present invention is to produce a simplified and improved shoe part ornamenting machine of the mask type in which the finished face of the shoe upper part may be, uniformly, the face into which the cutting edges of the die penetrate initially.

To the accomplishment of this object, and such

others as may appear hereinafter, the various features of the present invention reside in certain devices, combinations and arrangements of parts, hereinafter described and then set forth in detail in the appended claims, which possess advantages readily apparent to those skilled in the art.

Other features of the present invention reside in certain devices, combinations and arrangements of parts, hereinafter described and then set forth in detail in the appended claims, which possess advantages readily apparent to those skilled in the art.

The various features of the present invention will be readily understood from an inspection of the accompanying drawings, illustrating the best form of the invention at present known to the inventor, in which,

Figure 1 is a view in plan of the anvil, the shoe part being in a position for gaging;

Fig. 2 is a view in plan of the anvil, the gaged shoe part being in a position for ornamentation;

Fig. 3 is a detail view in plan of the cutting edges of the die, the stripper plate therefore, and two of the mask positioning pins;

Fig. 4 is a view in longitudinal sectional elevation of the anvil on the line 4—4, Fig. 1;

Fig. 5 is a view in elevation, partly in section, of the anvil illustrating how the masks may be tipped and swung about two axes substantially normal to each other, and

Fig. 6 is a detail view in sectional elevation, on the line 6—6, Fig. 3.

For convenience in disclosure the various features of the present invention are illustrated as embodied in an anvil usable in the cut-out machine of the type disclosed in the patent to Freeman, No. 1,681,033, August 14, 1928. It will be understood by those skilled in the art, however, that certain features of the present invention are not restricted to an embodiment in the anvil type of die, but may be, on the contrary, embodied in flat bed structures provided the cutting edges of the die thereof are upstanding and are associated with an overlying mask.

In the illustrated embodiment of the invention the anvil comprises a flat plate 1, (Figs. 4 and 5) the upper face of which is provided, rearwardly, with four posts 8 (Figs. 3, 4, and 5). These posts support a die base block 9 (Fig. 5). The block 9 is secured to the posts by four screws 10 the heads of which engage countersinks formed in the top face of a backing plate 11 engaged with the top face of the block 9. The backing plate 11 supports a die plate 12 which carries a plurality of tubes 13 each provided with an upstanding cut-

ting edge 14. The tubes 13 project upwardly through a soft rubber cushion 15.

Mounted upon the cushion 15 is a stripper plate 16 having openings therein through which the 5 cutting edges 14 may project when pressure is applied to the exposed face of the stripper plate. The bottom of the stripper plate 16 is provided with four depending posts 17 (Fig. 4) which extend downwardly loosely through openings 10 formed in the cushion 15, the die plate 12, the backing plate 11, and the base block 9. The upward movement of the stripper plate 16 under the influence of the rubber cushion 15 is limited by four screws 18 (Fig. 4) threaded into the bottom 15 of the posts 17. The heads of the screws 18 engage the bottom of the backing plate 11. With this construction the stripper plate 16 may be depressed by the pressing member of the cut-out machine to project the cutting edges 14 of the 20 tubes 13 through the openings in the stripper plate and the work supported above it. During this downward movement of the stripper plate the rubber cushion 15 is compressed so that when the pressing member of the cut-out machine 25 leaves the stripper plate it may be returned to its elevated position and thus strip the work from the cutting edges 14 of the tubes 13.

Heretofore in the operation of a cut-out machine of the type described, it has been customary to support the work directly upon the stripper plate and to clamp the supported work by a mask having an internal opening at least a portion of the edge of which is shaped to register with some portion of the supported work and thus 30 act as a gage in locating the work properly in position to receive the perforations or cut-outs.

In the illustrated embodiment of the invention the stripper plate 16 is engaged directly, not by the work, but by a mask 19. This mask 19 comprising 35 a flat plate 20 having an internal opening 21 therein (Fig. 2), some portion of which is shaped to act as a gage in locating the work properly in position to receive the ornamentations. The position of the mask 19 with relation 40 to the cutting edges 14 of the tubes 13 is determined by three pins 22, 23 and 24 (Figs. 1 and 2). The pins 22 and 23 project normally above the surface of the stripper plate 16. The heads 45 25 on the bottoms of the pins 22 and 23 ride in chambers 26 formed partially in the base block 9 and partially in the backing plate 11, the chambers being provided with springs 27, respectively, to maintain the heads 25 pressed against the tops of the chambers 26.

50 The pin 24 has a head 28 (Fig. 4) and a shoulder 29 both formed upon the upper end of a hollow post 30 loosely mounted in a chamber formed in a post 31 secured to the plate 7. The post 30 is provided with a recess 32 and the post 31 is provided with a screw 33 the point of which 55 engages the recess 32 thus to restrict the post 30 to a limited movement vertically. The post 30 is maintained normally elevated by a coiled spring 34 interposed between the bottom of the chamber 60 in the post 31 and the top of a chamber formed in the bottom of the post 30.

The mask 19 is provided with holes 35, 36, and 70 37 (Fig. 2) arranged to receive the pins 22, 23, and 24, respectively. The pins 22 and 23 pass loosely through the holes 35 and 36, respectively. The head 28 of the pin 24 passes loosely through the hole 37 but the bottom of the mask 19 rests upon the shoulder 29.

The work, herein shown as a made upper 38 75 (Fig. 1) closed by a heel seam 39 and lined with

a lining 40 (Fig. 2), is mounted between the mask 19 and a second mask 41 having an opening 42 (Fig. 1) and holes 43 and 44 identical in shape and location to the opening 21 and the holes 35 and 36, respectively, in the mask 19. The mask 5 41 is hinged to the mask 19 (Figs. 1 and 2) to facilitate the insertion of that portion of the work to be ornamented between the masks.

Assuming that the finished or grain face of the made upper is directly beneath the mask 41 when 10 the work is inserted between the masks 19 and 41, then some portion of the edge of the opening 42 is brought into registry with some portion of the upper 38 in the ordinary manner of using gaging masks in the perforating or cut-out art. 15 In order to clamp the masks and the gaged work together so that they may be handled as a unit, the mask 41 is provided with two pivoted arms 45 and 46 (Figs. 1 and 2) the free ends of which are provided, respectively, with a laterally offset 20 bent clip 47 arranged to extend under the mask 19 and clamp the masks and the gaged work embraced thereby.

Broadly considered the work may be inserted between the masks 19 and 41 and gaged, and the 25 masks 19 and 41 clamped together with the gaged work therebetween by an operative other than the operative of the cut-out machine. That is, by employing a plurality of holders, each comprising the masks 19 and 41, they may be loaded 30 with gaged work pieces and delivered to the operative for insertion into and removal from the cut-out machine. All the operative need do is position the clamped masks on the pins 22, 23, and 24, push the anvil into the machine, trip 35 the clutch, withdraw the anvil, and remove the clamped masks, leaving the duty of unloading the ornamented work to the operative charged with the duty of loading the masks.

With this construction and mode of operation 40 the operative of the cut-out machine may uniformly position the shoe parts to be ornamented in the cut-out machine so that the finished or grain faces of the shoe parts are directed towards the upstanding cutting edges of the dies thus to 45 insure that the edges of the perforations or cut-outs in the finished or grain face of the work shall be burnished and not burred.

In the illustrated embodiment of the present invention the front edge of the mask 19 is riveted 50 at its middle to a yoked-block 48 (Figs. 1, 2, 4, and 5). This block 48 is swiveled in a block 49 (Fig. 4). To this end the front face of the block 48 is provided with a cylindrical pin 50 journaled in the block 49. The pin 50 is held in the block 55 49 by a screw 51 the point of which engages a peripheral recess 52 formed in the pin 50.

The block 49 is pivoted between yoked arms (Fig. 4) formed on the upper end of a cylindrical post 53 mounted to slide vertically in a cylindrical chamber 54 formed in a post 55 carried by the plate 7. The post 53 is supported yieldingly by a coiled spring 56 interposed between the bottom of the chamber 54 and the bottom of the post 53. The vertical movement of the post 53 is limited by a screw 57 the point of which rides in a vertical recess 58 formed in the surface of the post 53.

Assuming that the masks 19 and 41 are empty and that the mask 19 is engaged with the stripper plate as shown in Fig. 4, the arms 45 and 46 on the mask 41 are swung outwardly to release it from the mask 19 and permit the mask 41 to be turned back upon its pivotal connection with the mask 19. The shoe part to be ornamented is 75

then placed in position on the mask 19, the grain or finished face of the shoe part being exposed to view. Then the mask 41 is swung down into engagement with the grain or finished face 5 of the shoe part which is then shifted under the mask 41 to bring some predetermined portion of the shoe part into registry with some predetermined portion on the edge of the opening 42. When the shoe part has been gaged the arms 45 10 and 46 on the mask 41 are swung inwardly to cause the clips 47 to engage under the mask 19 and thus clamp the masks 19 and 41 together with the gaged work therebetween. Then the operative swings the unitary structure, comprising 15 the clamped masks 19 and 41, forwardly on a horizontal axis, permitted by the pivotal connection between the block 49 and the posts 53, into the full line position of Fig. 5. Then the shoe upper part holder, comprising the clamped 20 masks 19 and 41, is swiveled on an axis, substantially normal to the horizontal axis, permitted by the connection between the pin 50 and the block 49 thus to reverse the relative position of the masks 19 and 41. Then the reversed masks 25 19 and 41 are returned to a position where the pins 22, 23, and 24 enter the holes 35, 36, and 37. The gaged work is now positioned with the grain or finished face of the shoe upper part directed towards the cutting edges 14 of the dies.

30 Now when the anvil is pushed into the machine beneath the pressing member thereof and the clutch is tripped, the presser member will come down upon the mask 19 and empale the shoe upper part upon the upstanding edges of the dies, 35 the pins 22, 23, and 24, the post 53 and the stripper plate 16 being depressed to permit the cutting edges to cut through the work.

When the shoe upper part has been ornamented the anvil is withdrawn from beneath the 40 pressing member of the cut-out machine, the masks 19 and 41 are unclamped, the ornamented shoe upper part is unloaded, and another shoe upper part is located in a gaged position between the masks 19 and 41. In this next succeeding 45 operation the mask 19 performs the function of a gaging mask. After the masks 19 and 41 have been clamped on the gaged work the position of the masks is again reversed to bring the gaging mask 19 down upon the stripper plate 16.

50 It is often highly desirable, in ornamenting shoe upper parts, that a fancy stitch design be correlated both with perforations or other cut-outs and impression or imitation stitch marking. In order to prepare a shoe upper part for the 55 fancy stitch marking operation it is necessary to place a guide line on the grain or finished face of the shoe upper part. In impression or imitation stitch marking the marks are placed also upon the grain or finished face of the shoe part. Notwithstanding its desirability, heretofore it has been impossible to correlate a fancy stitch design with impression or imitation stitch marking in any machine in which a mask overlying the marking means was used to gage the work. For 60 the mask must be used to register its positioning means with the fancy stitch guide line at a time when the grain or finished face of the shoe upper part is exposed to the operative's view through the opening in the mask. As the ornamenting means, at the time of gaging, is directed towards the flesh or lining side of the shoe upper part it is apparent that, with the prior art construction and mode of operation, it would be impossible both to gage from a fancy stitch guide 65 line on the grain or finished face of the work

and mark that same face with impressions or imitation stitches.

With the illustrated embodiment of the present invention, the stripper plate 16 may be provided with an impression or imitation stitch marker 59 5 (Fig. 3) in the manner disclosed in the patent to Woodworth, No. 1,733,638, October 29, 1929. In order to locate the shoe upper part properly relatively to the marker 59, the grain or finished face of the shoe upper part may be provided with 10 a guide line 60 (Fig. 1) in the machine disclosed in the patent to Woodworth, Reissue No. 17,715, reissued June 24, 1930. As indicated in Fig. 1 the front edge of the openings 21 and 42 in the masks 19 and 41 may be shaped to register with 15 the guide line 60. After the front edge of the openings 21 or 42 has been registered with the fancy stitch guide line 60 and the gaged work clamped between the masks 19 and 41, the position of the grain face of the shoe part may be 20 reversed in order to locate it properly to receive the impressions or imitation stitches from the marker 59.

In order to disclose the various features of the present invention in a simple manner the cut- 25 out forming means and the work ornamented thereby, have been illustrated and described, respectively, as perforating tubes and the vamp of a made shoe upper. Those skilled in the art will understand that the swiveled work holding and 30 gaging masks may be utilized advantageously in connection with other kinds of dies for forming ornamental cut-outs in various locations and in various kinds of shoe upper parts. For instance, to form cut-outs in quarter blanks it has 35 been necessary heretofore to employ two structures, one having a die, for forming the cut-out in a right quarter blank, and a mask, for gaging the right quarter blank, and the other having a die and a mask for the left quarter blank. By 40 utilizing swiveled work holding and gaging masks a single structure provided both with a die for the right quarter blank and a die for the left quarter blank may be employed. It will be apparent to those skilled in the art that if the 45 work holding and gaging masks are swiveled on an axis extending centrally between the two dies that the masks will gage a right blank when swung into a position over the right die and will gage a left blank when swung into a position 50 over the left die.

This may be illustrated by referring to Fig. 2. Sometimes the ornamental cut-outs are formed in the vamp on one side of the center line. In such a case, in order to cause the cutting edges of 55 the die to penetrate initially the finished or grain face of the right and left vamps, two dies must be employed, one for the right vamp and the other for the left vamp. If the masks are cut along the line 61 (Fig. 2) they could be used to 60 gage a right vamp to receive the ornamentations from the tubes marked collectively 62 (Fig. 2) and also could be used to gage a left vamp to receive the ornamentations from the tubes 65 marked collectively 63 (Fig. 2). That is, after the masks had been used to gage a right shoe upper blank for the operation of the right die, the masks could be then opened to unload the ornamented right shoe upper blank, closed to 70 locate the left shoe upper blank and then swung, first upwardly to clear the die, then laterally in the clear, and finally downwardly to locate the gaged left shoe upper blank in position over the left die. Thus, the swiveled masks may consti- 75

tute a universal gage for both right and left shoe upper blanks.

In fact, the single mask heretofore used with the stripper plate disclosed in the Freeman patent hereinbefore identified, may be converted into a universal gage for both right and left shoe upper blanks by swiveling the mask in the manner disclosed herein. That is, the plate 41 may be disconnected from the plate 19 and the plate 19 cut away along the line 61 (Fig. 2). Then the plate 19, when used with the Freeman stripper plate would, like the shoe upper blank gaging means (Fig. 2), constitute a gaging mask constructed and arranged to gage either a right or a left shoe upper blank at the will of the operative.

It will be clear to those skilled in the art and with the general objects of the present invention in view, that other changes may be made in the details of structure and mode of operation, the described and illustrated embodiment thereof being intended as an exploitation of its underlying essentials, the features whereof are definitely stated in their true scope in the claims herewith.

What is claimed as new, is:

1. In a shoe part ornamenting machine, the combination with perforating means and a support provided with mask positioning means, of at least two masks clamping therebetween the shoe part to be ornamented, at least one of said masks having position indicating means to insure the clamping of the shoe part in a gaged position, said masks being reversible to position the gaged shoe part over the perforating means and provided with devices cooperating with said positioning means to position the masks on the support both before and after reversal.

2. In a shoe part ornamenting machine, the combination with a support provided with pins, of at least two masks clamping therebetween the shoe part to be ornamented, said masks being provided with registering internal edges and holes, at least one of the internal edges insuring the clamping of the shoe part in a gaged position, said holes receiving the pins on the support to position the masks thereon.

3. In a shoe part ornamenting machine, the combination with ornamenting means, of a gage plate, provided with an opening through which the ornamenting means may project, mounted to tip about two intersecting axes.

4. In a shoe part ornamenting machine, the combination with ornamenting means and a work supporting plate provided with an opening through which the ornamenting means may project, mounted to tip about two axes intersecting substantially normal to each other, of a mask pivoted to the plate and provided with indicating means for determining the correct position of the work supported upon the plate.

5. In a shoe part ornamenting machine, the combination with ornamenting means and a work supporting plate, provided with an opening through which the ornamenting means may project, mounted to tip about two axes intersecting substantially normal to each other, of a mask pivoted to the plate and provided with an opening adapted to register with the opening in the plate.

6. In a shoe part ornamenting machine, the combination with ornamenting means, of a mask overlying the ornamenting means and mounted to tip about two axes intersecting substantially normal to each other.

7. In a shoe part ornamenting machine, the combination with a die and a post, each provided with at least one positioning pin, of a shoe part gaging mask provided with holes to receive said pins.

8. In a shoe part ornamenting machine, the combination with a die and a post, each provided with at least one yielding positioning pin, of a shoe part gaging mask provided with holes to receive said pins.

9. In a shoe part ornamenting machine, the combination with a die and a post, each provided with at least one positioning pin, and a second post, of a shoe part gaging mask pivoted on the second post and provided with holes to receive said pins.

10. In a shoe part ornamenting machine, the combination with a die and a post, each provided with at least one positioning pin, and a second post having a block pivoted thereto, of a shoe part gaging mask swiveled in the block and provided with holes to receive said pins.

11. In a holder for a shoe upper part, the combination with a plate mounted to tip about an axis and swing about another axis substantially normal to the first axis and provided with an internal opening, of a second plate pivoted to the first plate and provided with an opening adapted to register with the opening in the first plate, an edge of at least one of said openings serving as a gage for a shoe upper part inserted between the plates, and means for clamping the plates and the gaged shoe part for unitary handling.

12. In a shoe part ornamenting machine, the combination with ornamenting means, a pivot and a rotatable support therefor, of a shoe part gaging mask mounted on the pivot to swing from an operating position in which one face of the mask is directed towards the ornamenting means to a position clear of the ornamenting means, said pivot being rotatable on its support while the mask is in that clear position to permit the mask to be swung back to the operating position with its opposite face directed towards the ornamenting means.

ARTHUR W. ALTVATER.
